UNITED STATES PATENT OFFICE.

JOHN J. McCOMISH, OF NEW YORK, N. Y., ASSIGNOR OF ONE-THIRD TO FRANK J. REINECKE, OF HOBOKEN, NEW JERSEY.

PEN.

Application filed August 13, 1921. Serial No. 491,975.

To all whom it may concern:

Be it known that I, JOHN JAMES McCOMISH, a citizen of the United States, residing at New York city, in the county of New York and State of New York, have invented certain new and useful Improvements in Pens, of which the following is a specification.

This invention relates to stationery, and has particular reference to an improved means for attaching a pen nib to or detaching a nib from a pen holder, making use of a process or method of attachment through which the nib may be secured easily and quickly to the holder and firmly held in place for the usual purpose in such manner as to make its connection secure and sufficiently firm for the best and most satisfactory practice.

20 Among the objects of the invention therefore is to provide a convenient form of nib so designed as to make the attachment thereof to the holder easy and reliable, and especially without any possible injury to 25 the operator's fingers, and providing for the detachment of the nib from the holder at any future time with like facility and without any possibility of either injury to or soiling of the operator's fingers.

30 A still further object is to provide a pen for writing purposes that includes a holder of a very simple and cheap design and which is unusually neat and attractive in appearance as well as being well adapted 35 for the practical manipulation of the nib.

With the foregoing and other objects in view, but without restricting the invention unnecessarily as to materials, design, or the like, reference is had to the accompanying 40 drawings, in which similar parts are referred to by like reference characters, and in which—

Figure 1 is a dispersed view of the several main parts of the device.

45 Fig. 2 is a side view of the same assembled.

Fig. 3 is a longitudinal section of the holder carrying the locking device thereof in loose position ready for the reception of 50 a nib.

Fig. 4 is a detail view of another form of nib.

As indicated by the drawings my invention comprises two main parts,—a new type 55 of nib and a holder particularly designed

for co-operation therewith. The nib may be of various specific shapes but as indicated in Figs. 1 and 2 the nib 10 includes a shank portion having a pair of prongs 11 between which is a slot or opening 12. The 60 prongs lie essentially or practically in a plane substantially at right angles to the length or axis of the main portion of the nib or the axis of the holder 13 constructed for co-operation therewith. As indicated 65 the slot 12 is open at the bottom remote from the main shank or body portion of the nib, and from the upper portion of the base or shank portion is a lug or projection 14 extending rearward at right angles to 70 the base or prongs. This lug 14 may lie directly upon the surface of the holder or if preferred the holder may be formed with a depression 15 into which said lug may project.

The holder 13 in its broader aspects may be a cylindrical member of wood or the like having its lower end cut off flat and square or at right angles to the holder, and in the center of such end is formed a hole 80 16 for the reception of a binding member shown in the form of a round headed screw 17, the head of which is movable toward or from the end by a simple rotation of the screw toward the hole 16. Ordinarily the 85 binding member will be carried by the holder and remain attached thereto. As thus described, with the screw loosened slightly from the holder as indicated in Fig. 3, the prongs 11 may be slipped directly 90 down between the head and the end of the holder straddling the shank of the screw until the base or prong portion of the nib, which is practically circular, coincides with the end of the holder and with which it is substantially coextensive in outline, or if the lug 14 is employed until it is received in the notch 15, and then by giving the screw a slight rotation toward the right the head thereof will securely clamp the nib as 100 indicated in Fig. 2. The holder may be as large or small in diameter as the individual user may demand, as usual, but in no event will there be any parts projecting laterally 105 from the holder to interfere with the manipulation thereof in writing or the projection thereof into a bottle or the like.

In some cases it is preferred to provide a cushion between the base 11 of the nib and the end of the holder, and to this end I pro- 110

vide a rubber disk or washer 18 of about the same diameter as the end of the holder and intended to remain secured in such position by any suitable means, such as a film of cement 19. In addition to the cement indicated in Fig. 3, the cushion may be secured auxiliarly by means of a ferrule 20 fitted upon the end of the holder and having a projecting flange 21 taking into the periphery of the disk 18. The outer face of the disk however projects sufficiently far from the ferrule to permit the base portion of the nib to be plunged somewhat into the cushion while the clamping member 17 is being tightened. Some writers prefer the cushioning device, to afford a moderate amount of resiliency between the cushion and its holder. The provision of the lug 14 for the sake of others provides for reducing this flexibility of action between these parts. For maximum flexibility therefore I provide nibs as shown in Fig. 4 in which the base 11' of the nib is made with only the two prongs and without the lug 14.

The ferrule may be of ornamental metal if desired in the higher grades of holders, or it may be omitted entirely in the cheaper grades with very good satisfaction. The screw is provided preferably with a washer 22 of about the same diameter as the end of the holder so as to cover the slot or space 12 and the prongs. This washer may be separate from the screw or may be made as an integral part of the head. The base of the nib is gripped between said washer and the cushion 18 or end of the handle.

In the practice of this invention no matter how rusty or foul the pen holder may become from use or daubing with ink the nib may be easily and quickly removed simply by loosening the screw and allowing the nib to drop away from the holder. Any convenient screw driver or other similar tool may be employed to turn the screw, and for the purpose of removing the used nib the operator needs never to touch it with his fingers.

The holder, per se, is not claimed herein broadly but constitutes the subject matter of a companion application filed on the 25th day of October, 1922, Serial No. 596,759.

I claim:

1. In a writing pen, the combination of a holder having a flat end, a nib having a flat base attachment portion substantially coex-

tensive in outline with said flat end against which it lies, and means movable lengthwise of the holder to grip the nib against the said flat end.

2. In a writing pen, the combination of a holder having a flat end, a nib having a flat base attachment portion to lie against the holder end, and a screw fitted in the holder and having a head movable lengthwise of the holder against the flat base portion of the nib to grip the nib against the flat end of the holder.

3. A device as set forth in claim 1 in which the base portion of the nib comprises two spaced members lying in the same plane and the clamping means including a member projecting between said spaced members.

4. A pen holder having a flat nib-engaging end substantially perpendicular to its axis, and a cushioning member secured against said end.

5. A pen holder having an end, a pen nib having a base portion for co-operation with said end, and a threaded member movable at approximately a right angle to the nib base and longitudinally of the holder to grip the base of the nib against the end of the holder.

6. A pen nib having an attachment base portion arranged substantially at a right angle to the length or axis of the nib, said base having an opening in its edge remote from the body portion of the nib.

7. A nib as set forth in claim 6 in which said base portion comprises two spaced parallel prongs.

8. A nib as set forth in claim 6 in which said base portion includes a slotted structure through which a fastening member may be passed and also provided with a lug extending rearward from the base and at substantially a right angle thereto, said lug lying practically in alignment with the body portion of the nib.

9. A pen comprising a holder having an end substantially perpendicular to its axis and formed with a depression adjacent to the end, a nib having a base adapted to abut against said end and also having a lug projecting into said depression, and a fastening member acting directly through said base into the holder for securing the nib detachably thereto.

In testimony whereof I affix my signature.

JOHN J. McCOMISH.
